VACUUM CLEANER

Gustaf Einar Lofgren, Riverside, Conn., assignor
to Electrolux Corporation, New York, N. Y., a
corporation of Delaware

Application January 23, 1941, Serial No. 375,609

5 Claims. (Cl. 183—73)

My invention relates to vacuum cleaners and more particularly to vacuum cleaners of the type which are pulled around on the floor by a flexible hose.

Vacuum cleaners of this type are provided with a dust separating member or dust bag located within the vacuum cleaner casing. After the vacuum cleaner has been in use for a while the dust bag eventually becomes full and must be emptied. The vacuum cleaner casing is usually provided with a cover which may be removed to obtain access to the dust bag. After the dust bag has been emptied, it is usually immediately replaced in the vacuum cleaner casing. It is a customary practice to empty the dust bag at the end of each cleaning period. Occasionally the cleaner is returned to its storage place without replacing the dust bag. As a result, the cleaner may be operated without the dust bag in it. When this happens, the dirt and dust are carried into the fan and if the air passing through the cleaner is used, in whole or in part, for cooling the motor, it is also carried into the motor.

If a filter is provided between the dust bag and fan, it will stop the dust from entering the fan and motor. However, when a filter is so located serious damage may be done unless the mistake is discovered early because it will become clogged quickly and will stop the flow of air through the cleaner. This will cause the motor to overheat and even burn out if the condition is not corrected.

In accordance with this invention, a cover for obtaining access to remove the dust bag is provided which cannot be locked in position unless the dust bag is in the casing. Since this cover contains the inlet opening, it is impossible to use the cleaner without a dust bag in it.

What I consider to be novel and my invention may be better understood by reference to the following specification and appended claims when considered in connection with the accompanying drawings, in which

Fig. 1 is a side view of a vacuum cleaner with the casing broken away in part to expose parts beneath;

Fig. 2 is an enlarged side view of the front end of the vacuum cleaner casing broken away in part with the dust bag in position;

Fig. 3 is a view similar to Fig. 2 without any dust bag in the casing;

Fig. 4 is an enlarged detail view of the front of the casing broken away to show the cover locking mechanism;

Fig. 5 is an enlarged detail view looking in the direction of the arrows 5—5;

Fig. 6 is a detail section view taken along the line 6—6 of Fig. 4;

Fig. 7 is a view similar to Fig. 6 without a dust bag; and

Fig. 8 is a side view of the vacuum cleaner.

Referring to the drawings, 10 indicates a vacuum cleaner casing in which is mounted a motor 11 driving a multi-stage centrifugal fan 12. Fan 12 is adapted to produce a flow of air in casing 10 from left to right, as shown in Fig. 1. In the left end of casing 10, a dust bag 13 is located and serves to separate the dust from the air before it enters fan 12. A removable front cover 14 secures dust bag 13 in casing 10, as will be explained below, and permits access to remove dust bag 13 to empty it. A flexible hose 15 is connected in an inlet opening in cover 14 and communicates with the interior of dust bag 13. A cleaning tool 16 is connected to the other end of hose 15 by means of a rigid tubular handle member 17. When the area in the vicinity of the casing 10 has been cleaned, the casing 10 is moved to a new place by a pull on the flexible hose 15. This pull is transmitted from the hose 15 through the front cover 14 to the casing 10.

Dust bag 13 is secured to a ring 18 by means of binding thread 19. Ring 18 has an outwardly extending flange 20 which is covered with a rubber gasket 21. Gasket 21 rests in a seat 22 provided in a ring 23 secured to casing 10. Front cover 14 is provided with a corresponding seat 24 in which gasket 21 is received when cover 14 is secured to casing 10. When cover 14 is locked to casing 10, gasket 21 is compressed between cover 14 and ring 23 and provides an air-tight seal for cover 14.

Cover 14 is locked to casing 10 and disengaged therefrom by a handle 25. Handle 25 is rotatably mounted on a pin 26. Two gear sectors 27 are secured to handle 25 and rotatable therewith on pin 26. As best indicated in Fig. 4, gear sectors 27 engage two gears 28 pivotally mounted on plates 29 on opposite sides of handle 25. Similar gears 30, only one of which is shown, engage gears 28 and are pivotally mounted on plates 29.

Two fingers 31 are pivoted to plates 29 with integrally formed gear teeth engaging gears 30. Only one finger 31 is shown in Fig. 4. When handle 25 is in the position shown in Fig. 2, fingers 31 extend outwardly in locking engagement with bosses 33. When handle 25 moves from the position of Fig. 2 to the position shown in Fig. 3, the projecting portions of fingers 31 move down-

40

45

50

55

wardly from engagement with bosses 33 to a retracted position. Handle 25 is urged to the retracted position by a spring 34. As handle 25 is moved toward the latching position against the bias of spring 34, fingers 31 move upwardly against inclined surfaces 35 within bosses 33 compressing gasket 21 between cover 14 and ring 23, as shown in Fig. 6. The resilience of gasket 21 holds fingers 31 against inclined surfaces 35 producing a frictional force which retains the locking mechanism and handle 25 in latching position against the bias of spring 34. When the dust bag 13 is left out of casing 10, then there is no gasket 21 between cover 14 and ring 23, and so cover 14 rests directly on ring 23 and fingers 31 do not engage inclined surfaces 35, as shown in Fig. 7. Without any friction to resist the force of spring 34, it will be moved to the retracted position shown in Fig. 3. Even if the cover 14 should remain in position on bosses 33, there would be so much leakage of air between the cover 14 and ring 23 without gasket 21 that there would not be a sufficiently high suction produced to pick up any dirt at the cleaning tool 16. In addition, any pull at all exerted on the hose 15 would separate cover 14 from casing 10, as indicated in Fig. 8.

While a preferred form of the invention is illustrated in the drawings, it should be understood that the invention is not limited to the details of construction, as shown, but the scope of invention is pointed out in the appended claims.

What I claim is:

1. A vacuum cleaner including a casing, a removable dust separating member located in said casing, a removable cover securing said dust separating member in said casing, locking mechanism for said cover engaging said casing, spring means biasing said locking mechanism to a retracted position, and means removable with said dust separating member for resisting the biasing action of said spring.

2. A vacuum cleaner including a casing, a removable dust separating member located in said casing, a resilient gasket secured to said member, a removable cover engageable with said gasket to secure said dust separating member in said casing, locking mechanism for said cover engaging said casing, the resilience of said gasket urging said mechanism into frictional contact with said casing, and spring means tending to move said locking mechanism to a retracted position,

said spring having insufficient strength to move said locking mechanism against the resistance of said frictional contact when said dust separating member and said resilient gasket are in place in said casing.

3. A vacuum cleaner including a casing, a dust separating member located in said casing, a dust bag ring secured to said dust separating member and having an outwardly extending flange overlying an opening in said casing, a gasket secured to the flange of said ring and resting in a seat provided around the edge of the opening of said casing, a removable cover for the opening of said casing engaging said gasket and securing said dust separating member in said casing, a locking mechanism for said cover engaging said casing, said locking mechanism being held in the locking position by friction produced by compression of said gasket, and a spring means moving said locking mechanism to a retracted position when unopposed by said friction.

4. A vacuum cleaner including a casing, a dust bag located in said casing, a dust bag ring secured to said dust bag and having an outwardly extending flange, a gasket secured to the flange of said dust bag ring and resting in a seat provided around an opening in the casing for receiving said dust bag, a removable cover for the opening engaging said gasket, a locking mechanism for said cover engaging said casing, said locking mechanism compressing said gasket when moved to locking position and held in locking position by the friction produced by the compression of said gasket, and spring means biasing said locking mechanism to a retracted position.

5. A vacuum cleaner including a casing having an opening, a ring secured to said casing at one end forming a seat adjacent said opening, a dust bag adapted to be inserted through the opening of said casing, a dust bag ring secured to said dust bag and having a flange overlying the seat of said ring secured to said casing, a gasket secured to said flange and resting on the seat of said ring, a removable cover for the opening of said casing engaging said gasket, a locking mechanism for said cover engaging said casing and compressing said gasket to seal the opening of the casing and the friction produced by the compression of said gasket serving to hold said locking mechanism in a locking position, and spring means biasing said locking mechanism to a retracted position.

GUSTAF EINAR LOFGREN.
